UNITED STATES PATENT OFFICE.

JAMES L. BREESE, JR., OF CHICAGO, ILLINOIS, ASSIGNOR TO OIL DEVICES CORPORATION, OF CHICAGO, ILLINOIS, A CORPORATION OF ILLINOIS.

ISOTHERMAL-COMBUSTION CONTROL FOR OIL-BURNING HEATERS.

Application filed August 5, 1926. Serial No. 127,217.

My invention relates to a thermostatic or isothermal control for heaters and has for its particular purpose to provide an automatic fuel control particularly adaptable, although not limited to, a small hydrocarbon burning unit. One object of the invention is the provision of means for automatically controlling the fuel inlet valve in response to changes in temperature. Another object is the provision of such a valve controlling means, including an elongated element directly exposed to the heat of combustion. Other objects will appear from time to time in the course of the specification and claims.

I illustrate my invention more or less diagrammatically in the accompanying drawings, wherein—

Figure 1 is a vertical section;

Figure 2 is a detail sectional view of the top portion of the rod; and

Figure 3 is a detail section of the lower end of the rod and valve.

Like parts are indicated by like members throughout the specification and drawings.

A generally indicates a stove or burner unit having the lower cylinder A¹ and the upper cylinder A² with the intermediate connecting and supporting member A³ centered in the cylinder A¹ by the flange A⁴ and supported on it by the outwardly projecting flange A⁵. The member A³ terminates in the downwardly turned inner flange A⁶ about its central aperture.

B is any suitable cover member for the cylinder A² and is provided with the exhaust outlet B¹ with the chimney B².

C is an inner cylinder positioned within the cylinder A¹ and centered for example by the flange A⁶ of the member A³. It is provided with a generally concave bottom C¹ having the inlet opening C². It is herein shown as provided with an inner layer C⁸ of sand or similar finely divided material.

The member C¹ has screw threaded into it the valve body D, from which extends the fuel line D¹ outwardly through the cylinder A¹ to the fuel supply tank D². Such tank is provided with a top D³, generally horizontal partition D⁴ and a lower float chamber D⁵ with the float D⁶ therein. D⁷ generally indicates any suitable valve controlled by the handle D⁸ and adapted to engage the valve seat D² controlling the passage D¹.

The valve member D is provided with a valve seat D¹⁰ and a lower closure D¹² aligned therewith.

E is an inlet closure member in the top B of the stove. Screw threaded into it is the rotatable sleeve E¹ which may be controlled for example by the handle E² herein shown as having a hinged or pivoted extension E³. Loosely slidable in the sleeve E¹ is the hollow open-topped rod E⁴ to the top of which is screw threaded any suitable adjusting nut E⁵ for raising or lowering the rod in relation to the sleeve E¹ in which it is more or less loosely suspended. E⁶ are air apertures in the lower portion of the rod and E⁷ is a generally conical lower tip adapted to engage the valve set D¹⁰ in response to the extension of the rod E⁴. E⁸ is a needle valve designed to regulate the flow of air in the hollow rod E⁴. It is screw threaded in the bracket E⁹ secured to the upper end of the rod E⁴.

It will be realized that whereas I have described and shown a practical and operative device nevertheless many changes might be made in the size, shape, number and disposition of parts without departing from the spirit of my invention and I therefore wish my description and drawings to be taken as in a broad sense illustrative and diagrammatic rather than as limiting me to my specific showing.

The use and operation of my invention are as follows:

I provide a thermostatic control for a heater, herein illustrated as an oil burner, comprising a thermostatic member adapted to expand or contract in response to changes in temperature of the stove itself, or of its interior, such thermostatic member being preferably but not necessarily exposed directly to the heat and flame of the combustion of the fuel it controls. In the form herein shown I suspend a long rod from the top of the stove, the rod being supported in an adjusting nut and being normally so suspended that, when cool, the valve end of the bottom of the rod is somewhat withdrawn from a valve seat in the fuel line. Starting cold and the valve being thus withdrawn, a full or maximum flow of fuel is permitted. As combustion progresses and the flame grows hotter, the valve rod is directly exposed to it and expands. The stove

- as a whole also expands but the rod expands more rapidly and thus tends to restrict the flow of oil. By providing an adjustable support for the rod, for example the screw 5 threaded nut I am able to set the rod either to cut off the fuel altogether when heated to a predetermined temperature or else to reduce the fuel flow to a predetermined and controllable minimum. There can be no 10 cramping between valve and valve seat, no matter what the expansion of the rod or what the setting of the support, because the rod is loosely suspended or slidable in the adjustable support.
- 15 In order to prevent the rod from burning out and to prevent the formation of carbon on it I may provide an air circulation through the rod. This air circulation may be controlled by varying the cross-section of 20 the air passage, in the construction of the rod, or preferably, by varying the cross-section of the air inlet by adjusting means.

In case the rod is set to cut off the fuel altogether I preferably provide enough of a 25 fuel well in the fuel line to insure a store of fuel sufficient to maintain at least a slight flame until the cooling of the rod again withdraws it from the valve seat.

I claim:

- 30 1. A heating device and control therefor, including a burner, a fuel line extending thereto, a valve seat in said fuel line, and a thermostatic member comprising a hollow rod suspended above such valve seat and terminating in a valve member shaped to conform to such seat, and an outside air connection adapted to permit air to circulate through the interior of such rod.
2. A heating device and control therefor, 40 including a burner, a fuel line extending thereto, a valve seat in said fuel line and a thermostatic valve member and supporting means therefor, said thermostatic member adapted to approach and recede from said 45 valve seat in response to fluctuations in temperature, and being directly subjected to the flame of the burning fuel of the burner.

3. A heating device and control therefor, 50 including a burner, a fuel line extending thereto, a valve seat in said fuel line and a hollow thermostatic valve rod member and supporting means therefor, said thermostatic member adapted to approach and recede from said valve seat in response to fluctuations in temperature, and an outside air connection adapted to permit air to circulate through the interior of such rod.

4. A heating device and control therefor, 60 including a burner, a fuel line extending thereto, a valve seat in said fuel line and a hollow thermostatic valve rod member and supporting means therefor, said thermostatic member adapted to approach and recede from said valve seat in response to fluctuations in temperature, and an outside air con-

nexion adapted to permit air to circulate through the interior of such rod, and means for controlling such circulation of air.

5. A heating device and control therefor, including a burner, a fuel line extending thereto, a valve seat in said fuel line and a hollow thermostatic valve rod member and supporting means therefor, said thermostatic member adapted to approach and recede from said valve seat in response to fluctuations in temperature, and an outside air connection adapted to permit air to circulate through the interior of such rod, and adjustable means for controlling such circulation of air.

6. A heating device, and a control therefor, including a stove body, a burner there-within, a fuel line extending to the burner, a valve for said fuel line, the valve seat thereof being located beneath and in line with the top of said stove, and a thermostatic rod suspended from the top of said stove and extending downwardly through the burner and having a valve member at the lower end thereof adapted to engage said valve seat when the rod is extended in response to the heat of combustion.

7. A heating device, and a control therefor, including a stove body, a burner there-within, a fuel line extending to the burner, a valve for said fuel line, the valve seat thereof being located beneath and in line with the top of said stove, and a thermostatic rod suspended from the top of said stove and extending downwardly through the burner and having a valve member at the lower end thereof adapted to engage said valve seat when the rod is extended in response to the heat of combustion, the top of said rod projecting upwardly through the top of the 100 stove, the rod being hollow and being provided with an exterior air inlet and with air outlets positioned in the lower portion of the rod.

8. A heating device, and a control therefor, including a stove body, a burner there-within, a fuel line extending to the burner, a valve for said fuel line, the valve seat thereof being located beneath and in line with the top of said stove, and a thermostatic 115 rod suspended from the top of said stove and extending downwardly through the burner and having a valve member at the lower end thereof adapted to engage said valve seat when the rod is extended in response to the 120 heat of combustion and means for axially adjusting the position of said rod in relation to the stove top.

9. A heating device, and a control therefor, including a stove body, a burner there-within, a fuel line extending to the burner, a valve for said fuel line, the valve seat thereof being located beneath and in line with the top of said stove, and a thermostatic 125 rod suspended from the top of said stove and 130

extending downwardly through the burner and having a valve member at the lower end thereof adapted to engage said valve seat when the rod is extended in response to the 5 heat of combustion and means for axially adjusting the position of said rod in relation to the stove top, comprising a sleeve in screw fitted relation to the stove top.

10. A heating device and a control therefor, including a stove body, a burner therewithin, a fuel line extending to the burner, a valve for said fuel line, the valve seat thereof being located beneath and in line with the top of said stove, and a thermostatic 15 rod suspended from the top of said stove and extending downwardly through the burner and having a valve member at the lower end thereof adapted to engage said valve seat when the rod is extended in response 20 to the heat of combustion and means for axially adjusting the position of said rod in relation to the stove top, comprising a sleeve in screw fitted relation to the stove top, and a handle therefor, the rod being 25 slidably mounted in said sleeve.

11. A heating device and control therefor, including a burner, a fuel line extending thereto, a valve seat in said fuel line and a thermostatic valve member and supporting 30 means therefor, said thermostatic member being directly subjected to the flame of the burning fuel, and being adapted to approach and recede from said valve seat in response to fluctuations in temperature 35 caused by fluctuations in the flame of said fuel, and means, operable from the exterior of the heating device, for adjusting said

thermostatic member in relation to said valve seat.

12. A heating device and control therefor, including a burner, a fuel line extending thereto, a valve seat in said fuel line and a thermostatic valve member and supporting means therefor, said thermostatic member being directly subjected to the flame of the 40 burning fuel, and being adapted to approach and recede from said valve seat in response to fluctuations in temperature caused by fluctuations in the flame of said fuel, and means, operable from the exterior of the 45 heating device, for adjusting said thermostatic member in relation to said valve seat, said means including an adjusting member screw threaded in relation to the top of said heating device. 50

13. A heating device and control therefor, including a burner, a fuel line extending thereto, a valve seat in said fuel line and a thermostatic member being directly subjected to the flame of the burning fuel, and being adapted to approach and recede from 55 said valve seat in response to fluctuations in temperature caused by fluctuations in the flame of said fuel, and means, operable from the exterior of the heating device, for adjusting said thermostatic member in relation 60 to said valve seat, and a nut, in screw threaded relation with the upper portion of said rod, adapted to engage said adjusting member. 65

Signed at Chicago county of Cook and State of Illinois, this 28th day of July 1926.

JAMES L. BREESE, JR.
